MILK CARTON OR THE LIKE

Albert B. Mojonnier, Chicago, Ill., assignor to Albert Mojonnier Inc., Franklin Park, Ill., a corporation of Illinois

Filed Aug. 14, 1961, Ser. No. 66,344

Term of patent 14 years

(Cl. D58—17)

Fig. 1

Fig. 2

Fig. 3

FIG. 1 is a perspective view of a milk carton, showing my new design;

FIG. 2 is a side elevational view of the same; and
FIG. 3 is a top plan view of the same.

The dominant features of my design reside in the portions shown in full lines, a characteristic feature being the plain tapering upper and lower walls and the flange around the center.

I claim:

The ornamental design for a milk carton or the like, substantially as shown and described.
